(57) **CLAIM**

The ornamental design for an icicle light, as shown and described.

DESCRIPTION

FIG. 1 is a front perspective view of an icicle light, showing my design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of an area labeled 9 in FIG. 1; and,

FIG. 10 is an enlarged view of an area labeled 10 in FIG. 1. The broken lines in the drawings depict environmental structure and boundaries and form no part of the claimed design.
